PLATE WHIRLER

John D. Maxwell, Glen Head, N. Y., assignor to
 Powers Chemco, Inc., a corporation of New
 York

Application November 10, 1949, Serial No. 126,466

6 Claims. (Cl. 118—52)

1

This invention relates to an apparatus for evenly distributing and drying a wet coating on the surface of a flat plate, such as the sensitive coating on photo-engraving plates.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a view in vertical central section through the apparatus;

Fig. 2 is a horizontal section through the apparatus with certain parts shown in top plan view.

Fig. 3 is an enlarged section in plan aspect of the central portion of Fig. 2;

Fig. 4 is a vertical section taken along the lines 4—4 of Fig. 3;

Fig. 5 is a vertical section taken along the lines 5—5 of Fig. 3;

Fig. 6 is an enlarged section taken along the lines 6—6 of Fig. 2;

Fig. 7 is an enlarged section taken along the lines 7—7 of Fig. 2 and showing a characteristic movement of a portion of the apparatus; and

Fig. 8 is an enlarged vertical section taken along the lines 8—8 of Fig. 6.

One object of the invention is to provide convenient means for supporting plates of various sizes to be whirled, coated, and dried. Another object is to provide convenient means for coating and drying plates with a sensitive film with either the face or back of the plate toward the heat source, and means for automatically changing the speed of rotation of the plate depending upon which position the plate is in. A further object is to provide automatic braking means for slowing rotation of the plate being dried as it is moved from one position to the other.

Other objects and advantages of operation will appear to those skilled in the art upon study of the following description and the accompanying drawings.

Referring now to the drawings and particularly 55 gear 18' will not engage track 18. When the

2

to Figs. 1 and 2, there is provided a cylindrical shell 10 having a conical continuation 11 extending downward from its lower edge. The shell 10 is encased within an outer casing 12 of generally cubic shape.

A rotatable shaft 13 is journalled at opposite points of the shell 10 and is actuated by handle 14. Mounted at the approximate center of shaft 13, and secured against relative rotation therewith, is a plate holding and whirling assembly including plate-gripping jaws 16 and friction gear tracks 17 and 18, adapted to be driven by friction gears 17' and 18' respectively.

The jaws 16 are equally step-notched so as to enable various sized plates to be gripped by them. As shown in Figs. 2 and 3, the jaws 16 are normally urged toward each other by springs 20. As will be seen in Figs. 3 and 4, the jaws 16 are arranged as a spaced integrally joined pair of jaws 16a and 16b on either side of the gear tracks 17 and 18. They are so spaced and joined by plates 19 and 19'. The jaws 16 are moved away from each other, against the tension of springs 20, by depression of the foot treadle 22. This action draws chain 23 over pulleys 24.

This movement causes lug 26 to engage with lug 27 and urge it and the pair of jaws 16a or 16b to which it is integrally attached to move away from the axes of rotation. Lug 26 is normally urged toward the axes of rotation by spring 28. Spring 28 is connected on one end to plate 29 on the end of chain 23 and on the other on eye bolt 31 fixed in journal housing 25. This movement causes the opposite pair of jaws 16a to move complementarily away from jaws 16b by means of the double lever arrangement 30 shown in Figs. 2, 3, 4 and 5. A plate is inserted between jaws 16, the treadle 22 is released and the plate is gripped firmly by the jaws 16.

The plate whirling assembly including the jaws 16 and gear tracks 17 and 18 rotate in a horizontal plane about a vertical axis 32 shown in Figs. 1—4. The whirling assembly is also rotatable about a horizontal axis 33 for moving the assembly from an upward facing to a downward facing position as shown in Fig. 1. The horizontal axis 33 runs through the axial center of shaft 13 and the vertical axis 32 runs through the axial center of shaft 35. These respective axes are at right angles to each other but are offset from each other. Thus, when the plate whirling assembly is in face-up position the vertical axis 32 will be on the side of the horizontal axis 33, as shown in Fig. 1, permitting gear 17' to engage gear track 17, while

whirling assembly is rotated to the face-down position, also as shown in Fig. 1, the vertical axis 32 will still be offset from the horizontal axis 33 but in a different plane than in the face-up position. This will permit gear 18' to engage track 18. The gear ratio of gear 17' to track 17 is about 1 to 5, while that of gear 18' to track 18 is about 2 to 5. This will enable plates held in the face-down position to be whirled at much higher speeds.

As shown in Fig. 4, the vertical shaft 35 is mounted in a bearing block 36 common to it and horizontal shaft 13, by means of roller bearing 33 and pin 39. The shaft 35 is bolted to the upper portion of the whirling assembly through an integral flange 40.

Friction gears 17' and 18' are driven in the following manner. An electric motor 45, as shown in Fig. 1, drives vertical shaft 46 through a reducer 47. Vertical shaft 46 in turn drives horizontal shaft 48 by means of bevel gears 50. At the other end of shaft 48 from the bevel gears 50 are the friction gears 17' and 18'.

Located in the bottom center of the conical portion 11 is a gas burner 52 which is actuated by a solenoid valve 53. This valve is actuated by the timer 57 in such a fashion that operation of switch 54 provides a longer time interval for copper plates than that provided for zinc plates. Mounted near switch 54 is starter 55 which starts electric motor 45 and timer 57.

In turning a whirling plate from a face-up to a face-down position, braking means are provided. As shown in Fig. 2, these consist of a pair of fixed shafts 60 carrying brake shoes 61. The braking means are shown in enlarged detail in Fig. 7. The brake shoe 61 is secured to a block 63 mounted on a plunger 64 which is springably urged away from shaft 60 by means of spring 65 mounted within shaft 60.

When the gear track member is rotated from face-down to face-up position, or vice versa, gear track 17' will bear against brake shoe 61, causing a braking action on the rotation of the whirler assembly. Obviously the whirler is rotating freely when it is in a substantially horizontal position.

In Fig. 6 is shown a slop cover 70 to prevent drippings from the whirled plate from falling on the chain 23 and other moving parts directly under it. Fig. 8 also shows the slop cover 70 and its relation to the chain 23.

The construction and operation of the double lever arrangement 30 is as follows. In Figs. 3 and 4 are two facing circular plates 73 and 74 journaled about housing 75. These plates have connecting bars attached to them in the following manner. Bar 30a is pivotally attached to the upper portion of plate 19 and the upper portion of plate 73. Bar 30b is pivotally attached to the upper portion of plate 19' and the upper portion of plate 73. Bars 30c and 30d are similarly attached to the lower sides of plates 19 and 19' and the lower side of plate 74. Thus, when plate member 19 is drawn away from the axis of rotation, bars 30a and 30c will cause plates 73 and 74 to rotate in opposite directions thus causing bars 30b and 30d to push plate 19' away from the axis of rotation, causing jaws 16 to move equally away from each other.

The method of operating the apparatus may be as follows:

The operator approaches the machine with a clean plate P while it is still wet from cleaning. He places the plate in the machine where it is

gripped by the jaws 16, starts the motor 45, whirling the plate face up, and pours the required quantity of coating on the wet plate. He then turns handle 14 inverting the plate to a face-down position where it runs at the higher speed, throws off excessive coating and is gradually dried, while still in a face-down position. In some instances the machine is set so that when the gas is turned the timer starts when the plate

10 P is reversed, but the machine is perfectly useable and may be manufactured in either form.

Because of the offset of the vertical axis 32 from the horizontal axis 33, and the braking means 60, 61, it is possible to change the speed of rotation of the plate or its facing position without stopping the motor 45 or burner 52.

The timer 57 automatically stops the motor 45 and burner 52, and the plate comes to rest. The treadle 22 is then depressed, releasing the grip of jaws 16 on the plate P and permitting its removal.

The invention in its broader aspects is not limited to the specific embodiment shown and described but departures may be made therefrom within the scope of the accompanying claims without departing from the principles of the invention and without sacrificing its chief advantage.

What is claimed is:

1. In a photoengraver's plate whirler, the combination of a holder for rotatably supporting a plate to be coated and then dried, a circular friction surface on the side of said holder opposite the side where the plate is held, the circular friction surface comprising two concentric tracks, a pivotally mounted bearing in which the holder is rotatably journaled, the pivotal axis being at right angles to the axis of rotation but offset therefrom, so that the holder may be 35 swung from one horizontal position with the side where the plate is held uppermost to another horizontal position with the side where the plate is held lowermost, and two driven friction wheels one of which is engageable with one of said tracks and the other with the other track to drive the holder at different speed when the holder is in one or the other of its horizontal positions.

2. A plate whirler as claimed in claim 1 in which the two friction wheels are mounted on a common driven shaft at right angles to both the pivotal and rotational axes.

3. In a plate whirler the combination of a holder for rotatably supporting a plate to be coated and then dried, a shaft on which the holder is mounted, a pivotal bearing for the shaft, said pivotal bearing being offset relatively to said shaft but at right angles thereto, a pair of concentric circular tracks on the side of said holder opposite the side where the plate is to be held, and a shaft having spaced driven friction wheels thereon, one wheel engageable with one track in one horizontal position of the holder and the other wheel engageable with the other track in inverted position of the holder.

4. A plate whirler as claimed in claim 3 in which the holder has radially movable jaws, resiliently urged towards each other and interconnected to move equally towards and from the center, and means engageable with a jaw with the holder in its upper position for moving said jaws apart.

5. A plate whirler as claimed in claim 4 in which a friction member resiliently engages the holder, as it is inverted, for slowing rotation of the holder.

6. A plate whirler as claimed in claim 4 in which the jaws are interconnected by a double lever arrangement comprising two facing circular plates journaled about a common bearing, one plate having a pair of connecting bars pivotally attached to it at opposite points, one of said bars being pivotally attached to a member integral with one jaw and the other bar being connected to a member integral with another jaw, and another pair of connecting bars being attached in a similar manner to said other plate, and members integral with said jaw, said con-

nctions of said bars to said plates being adapted to rotate said plates in opposite directions when one jaw is moved away from the other thus causing the other jaw to be equally displaced.

JOHN D. MAXWELL.
